UNITED STATES PATENT OFFICE

WILLIAM A. CHAPMAN, EDWARD J. MACHEMER, AND FREDERICK J. PAUL, OF SILVER CREEK, NEW YORK, ASSIGNEES TO HUNTLEY MANUFACTURING CO., OF BROCTON, NEW YORK, A CORPORATION OF NEW YORK

CORING MACHINE

Application filed May 19, 1928. Serial No. 279,028.

Our invention relates to improvements in coring machines, and more particularly to that type of machine or apparatus especially adapted for coring tomatoes, preparatory to canning or otherwise preserving the same; it being, however, understood that the machine or apparatus may be used for removing the centers or portions of the centers of other fruits or vegetables.

10 One of the objects of our invention is the provision of a simple and inexpensive machine of this kind, in which a movable guard is provided to prevent the coring knife from injuring the operator when the machine is running idle, and which guard is utilized as the medium for operating said knife and causing it to enter the tomato or other article to be cored.

20 Another object of our invention is to provide a novel rotatable head which carries the cutting or coring device in eccentric relation thereto, and which cutting or coring device is suitably controlled to enter the tomato or other article to be cored off-center and be moved to or towards the center or axis of the article.

25 Other objects of our invention are to improve the manner of supporting the cutting or coring device and spring-retaining the same; to simplify the construction of coring machines of this kind; to minimize the number of parts in use; and to otherwise improve on coring machines now in use.

With the above and other objects to appear hereinafter, the invention consists in the novel features of construction, and in the arrangement and combination of parts to be hereinafter described, and more particularly pointed out in the subjoined claims.

40 In the drawings:

Fig. 1 is a sectional side elevation of the machine, as shown in duplex form with a single driver for operating both parts thereof.

45 Fig. 2 is a detached perspective view of the rotatable knife-carrying head.

Fig. 3 is a detached perspective view of the knife carrier.

50 Fig. 4 is a detached perspective view of the coring knife.

Fig. 5 is a section through one end of the machine taken on line 5—5, Fig. 6.

Fig. 6 is an end view of the machine.

Fig. 7 is a transverse section taken on line 7—7, Fig. 1, looking towards the left.

Fig. 8 is a similar section looking towards the right.

Fig. 9 is a transverse section taken on line 9—9, Fig. 1.

Fig. 10 is a side elevation of a modified form of knife carrier and a portion of the rotatable head to which said knife carrier is pivotally secured.

In the exemplification of our invention shown, we have provided a duplex machine in which the operation of coring tomatoes or other articles is performed at each end of the machine, and for this purpose a central frame or support 11 is provided having upstanding walls 12 at each end, a base 13 connecting the lower ends of said upstanding walls, bearings 14 extending inwardly toward each other from said walls, and webs 15 connecting the base with said end walls and bearings and serving to provide the necessary rigidity for the frame.

The bearings 14 are spaced apart and in them is journaled a shaft 16 to which is keyed or otherwise secured a pulley 17, around which a belt (not shown) may be placed for rotating the shaft. This shaft extends with opposite ends beyond the end walls 12 of the frame, and on each end a coring mechanism is mounted.

As the coring mechanisms are exact duplicates, a description of one will suffice for both; but it may here be stated that fastened to each end of the shaft 16 is a head 18 which may be referred to as a rotatable knife-carrying head, for reasons to presently appear.

In the preferred form, this head 18 is provided with a screw-threaded opening 19 into which a set-screw 20 is threaded; the inner end of this set-screw engaging a flat surface 21 formed on the shaft 16 by providing a depression therein. A jamb nut 22 surrounds the set-screw 20 and guards against unloosening of the set-screw and consequently the head from the shaft. The head 18 has two spaced outwardly-extending arms 23 which

are disposed off-center and between them a knife carrier 24 is pivotally secured; a pivot 25 being passed through said arms and the knife carrier. This knife carrier is in the 5 form of a lever which extends in opposite directions from the pivot 25, one end thereof having a head 26 grooved, as at 27, to receive the enlarged end 28 of a cutter or coring knife 29.

10 The enlarged end 28 of the knife has an opening 30 therethrough, through which a securing screw 31 is passed and entered into the head 26 of the knife carrier, thus securing the cutter or coring knife to said carrier in a 15 manner to extend therefrom at substantially a right angle thereto. The opposite end of the knife carrier is provided with a screw-threaded opening 32 disposed at a right angle to the pivot 25, and in this threaded opening 20 32 is arranged a stop screw 33 held in adjusted position by a jamb nut 34.

The knife carrier has an inwardly-projecting lug 35 formed thereon, between its pivot and the head 26 thereof, and fastened to said 25 lug is one end of a retractile spring 36, the other end of which is fastened to the shaft 16, which is bored out, as at 37, from each end; and through this bored-out portion, at the inner end thereof, a pin 38 is passed to which so the inner end of the spring 36 projecting into said shaft, is secured. The inner end of the spring 36 is therefore axially secured to, and within the shaft, and the outer end thereof is secured to the knife carrier in substantial 55 alinement axially with said shaft when the knife carrier is retracted by the spring.

Adjustably supported from each end wall 12 is a guard in the form of a plate 39, which also serves as an actuator for the cutter or 40 coring knife, and as part of a housing for enclosing the rotatable head 18 and the knife carrier 24; also other parts of the device, as will appear hereinafter. For this purpose the outer end of bolts 40, three in number and 45 equally disposed around the head 18, are fastened to the guard or actuator 39 and pass through openings 41 formed in the end walls 12.

Between the guard or actuator and the 50 end wall 12 of the frame 10, spiral springs 42 are disposed, which surround the bolts 40 and keep the guard plate 39 spaced a definite distance from said end wall. The bolts 40 are slidable through the openings 41 in the end wall 12 and have stop nuts 43 threaded thereonto so as to bear against the inner surface of said end wall and thus prevent the outward travel of the guard or actuator beyond the position predetermined therefor. 55 The exact position of the guard or actuator may be varied by adjusting the nuts 43 on the bolts 40.

The space between the guard plate and the end wall 12 of the frame 10 is enclosed 60 at the sides and top by a substantially U-

shaped shield or cover 44 fastened in any suitable manner along its rear marginal edge to the end wall 12 of the frame.

Arranged in the guard or actuator 39 is an opening 45, the axis of which is co-incident with that of the head 18 and the shaft 16, and the cutter or coring knife 29 normally extends into this opening.

On the inner side of the guard or actuator 39 is a wear annulus 46, which is riveted or otherwise fastened thereto; it being preferably constructed of hard material, and against it is adapted to bear the stop screw 33, this stop screw being pressed thereagainst through the action of the spring 36 80 and consequently when the knife-carrying head 18 is being rotated, the stop screw 33 travels circularly and in contact with the wear annulus 46.

The tomato or other article to be cored, 85 shown for example by the dotted lines in Figs. 1 and 5 and designated by the numeral 47, is placed against the outer side of the guard or actuator 39 with its center or axis in alinement or substantially in alinement 90 with the axis of the opening 45; and through the medium of the tomato or other article to be cored, the guard or actuator 39 is forced inwardly against the action of the springs 42, causing the bolts 40 to slide through the 95 openings 41 in the end wall 12 of the frame. During this action, the knife carrying head 18 is in rotation, causing the knife to travel circularly and at the same time to move outwardly through the opening 45, swinging 100 on the pivot 25 as its center. Thus, while entering the tomato or other article, it is gradually being moved toward the axis of the article, as indicated in Fig. 5. The tomato or other article is held against rotation 105 by the operator, and due to the fact that the knife is traveling in substantially a circular path while being forced outwardly, the core of the tomato, indicated by the dotted lines 110 in Fig. 5, is severed from the remainder 115 of the tomato during a complete cycle or travel of the knife in a circular course. It will therefore be apparent that the operation of coring a tomato is quick and certain, and that it can be most efficiently accomplished by inexperienced help. Removing the tomato 120 so cored from the guard plate permits the springs 42 to return the guard or actuator to normal position, which position is determined by the stop nuts 43 on the bolts 40.

For the purpose of limiting the inward movement of the guard or actuator, we have provided two stop screws 49, these being threaded through the end wall 12 of the frame 10 from the inner side thereof, and the spacing of the outer end of these stop screws from the wear ring 46 on the inner side of the guard or actuator determines the range of movement of the latter; sufficient movement only of said guard or actuator 130

being necessary to bring the cutter or coring knife from the position, or substantially the position, shown in Fig. 1 to that shown in Fig. 5.

5. The core severed from the remainder of the tomato may pass through the opening 45 of the guard or actuator and drop downwardly through the open bottom of the housing, formed in this particular embodiment of our invention, by the guard or actuator 39, the end wall 12, and the U-shaped shield or cover 44.

With the parts in substantially normal position, such as shown in Fig. 1, the retractile spring 36 is axially alined with the shaft, but during the outward movement of the cutter or coring knife 29, this spring is moved slightly out of axial alinement with the shaft, as indicated in Fig. 5. To permit of free action of this spring under such conditions, the outer end of the bored portion of the shaft is flared, as at 50.

In the modification shown in Fig. 10, we have illustrated a curved knife, having the curvature on the center of the knife carrier 29 so that the knife will enter a tomato or other article without possibility of tearing or shedding any of the meat of the same.

Under the basic idea involved in this invention, it is not essential that the elements be particularly shaped or formed, and related, supported, or connected, as shown, as various modifications may be resorted thereto without departing from the spirit of our invention, or sacrificing any of the advantages thereof. The machine may be constructed as a single machine, or in the form shown, in which a cutting or coring device is provided at each end of the frame, both cutting or coring device being actuated by a single shaft and a prime mover, such as the pulley 17 secured to said shaft.

Having thus described our invention, what we claim is:—

45. 1. A machine for coring tomatoes and the like, comprising a coring knife adapted for circular travel and a guard against which the tomato to be cored is placed, said guard being movable parallel to the axis of the circular path of said coring knife, and means between said guard and said coring knife to thrust said knife through said guard into the tomato componently with its circular course of travel when moving said guard.

55. 2. A machine for coring tomatoes and the like, comprising a rotatable knife-carrying head, a coring knife pivotally applied to said head and disposed off-center thereon so as to travel in a circular path during rotation of said head, and non-rotatable means for actuating said knife during its travel to swing it on its pivot into the article being cored and towards the axis thereof, said non-rotatable means being actuated under pressure applied to the article being cored.

3. A machine for coring tomatoes and the like, comprising a rectilinearly-movable guard spring-retained at the end of its movement in one direction and against which a tomato or the like is adapted to be placed for moving the same under pressure in an opposite direction, a circularly-traveling knife mounted for component movement toward and from the axis of said circular movement, and means between said guard and said knife to thrust the latter into the tomato upon movement of said guard in one direction.

4. A machine for coring tomatoes and the like, comprising a rotatable shaft, a head secured to said shaft, a knife carrier pivotally mounted for swinging movement on said head and spring-retained in one of its two extreme positions, a knife secured to said carrier and movable toward and from the extended axis of said head, an actuator having an opening therethrough and the axis thereof coincident with the axis of said head and against which a tomato or other article to be cored is adapted to be placed, means to keep said actuator in normal position, means interposed between said knife carrier and said actuator to cause the knife on said carrier to be projected through the opening in said actuator and enter the tomato upon movement of said actuator, and means to return said actuator to normal position.

5. A machine for coring tomatoes and the like, comprising a frame, a shaft rotatably in said frame and projecting therefrom, a head secured to the projecting end of said shaft, a knife carrier pivotally secured to said head, an actuator spaced from said frame and spring-retained a predetermined distance therefrom, said actuator being yieldably movable toward said frame, stop means to limit the movement of said actuator toward said frame, and means interposed between said knife carrier and said actuator to cause swinging movement of said knife carrier.

6. A machine for coring tomatoes and the like, a rotatable knife-carrying head, a knife carrier pivotally secured to said head off-center, a knife secured to said carrier and adapted to travel through a circular path during rotation of said head, and non-rotatable means for actuating said knife carrier to cause it to swing on its pivot while rotating with said head, said non-rotatable means being actuated by the article being cored under pressure applied thereto.

7. A machine for coring tomatoes and the like, comprising a frame having an end wall, a shaft journaled in said frame and projecting beyond the outer surface of said end wall, a guard spaced from said end wall, guide elements carried by said guard and guided for movement in said end wall, springs surrounding said guide elements and serving to hold said guard in predetermined spaced relation to said end wall, stop-means on said guide ele- 130

- ments to limit the movement of said guard away from said end wall, stop means on said end wall to limit the movement of said guard toward said end wall, a rotatable head on said 5 shaft, a lever pivotally connected between its ends to said head off-center, a knife secured to one end of said lever and adapted to be projected through said guard, stop means to limit the inward movement of the knife-car- 10 rying end of said lever and to cause outward movement of said end upon moving said guard toward said end wall, and a spring for retaining said lever in normal position.
8. A machine for coring tomatoes and the 15 like, comprising an element against which a tomato or the like is to be placed for coring the same, a knife pivotally mounted and adapted to be thrust into the tomato and toward the axis thereof under movement of said 20 element, a rotatable mounting for said knife to cause it to travel in a circular course, and means for rotating said mounting.
9. A machine for coring tomatoes or the 25 like, comprising an element against which a tomato or the like is to be placed for coring the same, a knife pivotally mounted and adapted to be thrust into the tomato and toward the axis thereof, a rotatable mounting for said knife to cause said knife to travel in 30 a circular course, and non-rotatable means to cause said knife to swing on its pivot and actuated directly by the article being cored under pressure applied thereto.
10. A machine for coring tomatoes and the 35 like, comprising a rotatable element, a knife carried thereby to cause the same to travel in a circular course during the rotation of said element, an element against which a tomato to be cored is adapted to be placed, and means 40 between said last-mentioned element and said knife to thrust said knife into the tomato and toward the axis thereof.
11. A machine for coring tomatoes and the 45 like, an element against which a tomato is adapted to be placed, and a circularly traveling knife movable toward and from the axis of the tomato under movement of said element to cause the core of the tomato to be removed therefrom during the circularly 50 traveling movement of said knife.
12. A machine for coring tomatoes and the 55 like, comprising a frame, a shaft journaled in said frame and extending outwardly therefrom, an actuator in the form of a plate having an opening therethrough and against which a tomato is to be placed to be cored, said tomato covering said opening, a knife-carrier head secured to said shaft between said frame and said actuator, a knife carrier in 60 the form of a lever pivoted between its ends to said head at one side of its center, a wear annulus on the inner side of said actuator, adjustable means carried by said knife carrier and in contact with said wear annulus, and a 65 knife carried by said carrier adapted to be

projected through the opening of said actuator and enter the tomato to remove the core therefrom upon manipulation of said actuator.

13. A machine for coring tomatoes and the 70 like, comprising a shaft, a head secured to the end of said shaft and having two spaced outwardly-extending arms disposed off-center on said head, a lever pivotally secured between its ends between said arms, said lever having a coring knife at one end and an adjustable stop screw at its other end, and a plate provided with an opening whose axis is coincident with that of said head and through which opening said knife is adapted to be projected, said plate having said stop screw in contact therewith to cause said lever to swing on its pivot upon movement of said plate toward said head.

14. A machine for coring tomatoes and the 85 like, comprising a frame, a shaft journaled in said frame and projecting therefrom, the projecting end of said shaft being cored out and having a pin extending transversely through said cored-out portion at the inner end thereof, a head secured to the projecting end of said shaft and having a pair of outstanding spaced arms arranged off-center, a knife carrier pivotally connected between said arms and having a coring knife extending therefrom adapted to travel in a circular path, a retractile spring having one end secured to said knife carrier and extending into the cored-out portion of said shaft, said spring having its other end secured to said transverse pin, 100 an element against which a tomato to be cored out is placed, and co-acting means between said element and said knife carrier to cause the knife of said carrier to be projected through said element and into the tomato when exerting pressure against said element and while the knife is traveling in a circular path.

15. A machine for coring tomatoes and the 110 like, comprising a frame, an actuator spaced from said frame and against which a tomato to be cored out is adapted to be placed, a coring knife between said actuator and said frame arranged to travel in a circular path, means for causing said knife to so travel, and means to thrust the knife into the tomato toward the center thereof while traveling in a circular path, said means being actuated by the article being cored under pressure applied thereto.

In testimony whereof we affix our signatures.
